METHOD OF CRACKING OILS

Drue M. Evans, Wood River, Ill., assignor to
Petroleum Conversion Corporation, New York,
N. Y., a corporation of Delaware

Application October 28, 1935, Serial No. 47,035

6 Claims. (Cl. 196—61)

My present invention relates to a method of cracking oils, preferably in the vapor phase, by the agency of hot gas constituted in substantial part at least by the exhaust of an internal combustion engine. By suitably modifying the method of operating an internal combustion engine, it is possible to produce a stream of gas having a temperature of 1100 degrees F. or more and at a pressure say up to fifty pounds or more which 5 I have found to afford a satisfactory medium for the cracking of oil in the vapor phase. Preferably, two or more engines are used and the exhaust from these collected, a reservoir or surge chamber being employed if desired. The oil to 10 be cracked is preferably vaporized and, if desired, the vapor produced is superheated, and the vapor which is below the temperature of active cracking mingled with the hot gas and the reaction allowed to proceed in a reaction chamber, the 15 mixture of products then progressively dephlegmated so as to yield finally a desired product of the cracking, as for example a distillate in the gasoline range, leaving a stream of gas which is more or less saturated with light vapors. 20 Desirably, the latter are recovered preferably by the use of an absorber whereupon the stripped gas which comprises not only the combustion gases originally present but the gas formed by the cracking of the oil or oil vapor, (the latter 25 varying in amount say from 8 to 15% of the oil admitted to the system for cracking), is utilized as fuel for the internal combustion engines, such mixture being of sufficient fuel value for this purpose. When the fat oil from the absorber mentioned 30 is heated, a gas is liberated of high thermal value and this preferably is added to the gas fed to the internal combustion engines. The superfluous gas which is not required as fuel in the engines is used in various parts of the plant 35 requiring heat, as for example for operating the vaporizer for the oil to be cracked. The energy obtained by burning the gas in the various engines may be used for many purposes, including especially that of compressing the gases in the 40 system prior to their admission to the absorber.

Some of the gas may also be heated by heat exchange with the dephlegmated products and the gas so heated added directly to the reaction chamber. 45 The invention will be best understood by reference to the following detailed description taken with the annexed drawing in which the figure represents diagrammatically a plant containing an 50 illustrative embodiment of the invention. The 55 exhaust gases from engines 10, 11 and 12 (the

number of engines being arbitrary) are collected in a main 13 by means of the connections thereto numbered 10a, 11a, 12a, said main being joined to a mixing chamber 15 by means of branch 14. Also admitted to chamber 15 through line 16 is a supply of oil, preferably in vapor form, to be cracked. To supply this, the oil is admitted preferably to a heating coil 17 passing by way of pipe 18 to a flash chamber 19, the vapor from this being preferably superheated by being passed through pipe 20, superheating coil 21 and finally to pipe 16. If superheated, the vapor may thereupon have a temperature of from 850 to 1000 degrees F. whereas the hot gas will have a temperature preferably in the neighborhood of 1100 degrees F., it being understood that these temperatures may be varied considerably depending upon the initial cracking temperature desired, and the amount of superheating of the vapors, if any. The initial cracking temperature will 20 ordinarily be chosen around 1000 degrees F. After mixing in the chamber 15, the intermingled gas and vapor passes through a connection 22 into reaction chamber 23 where the reaction is completed. The products leave chamber 23 through pipe 24 and pass to fractionator 25, the same consisting preferably of a combined scrubber and rectifier. Progressive dephlegmation takes place throughout the column from which the heaviest component or residue is led off through pipe 26, 30 the same passing through heat exchanger 27 and admitted back into the column through pipe 28 at a point say a third of the way up. Also into pipe 28 may be admitted a fresh feed of oil to be treated through pipe 29. A portion of the heaviest fraction is withdrawn from the system through connection 29a. Somewhat above the bottom of the column there is taken off a fraction of intermediate boiling point which may be termed a gas-oil fraction, the same passing 35 through pipe 30 into vaporizer 17 to enter into the cracking cycle. Also, if desired, all or a portion of the fresh feed may be admitted through said pipe to connection 31. Finally a gasoline fraction is withdrawn at or adjacent the top of the 40 column through pipe 33 and collected in an accumulator 34, a portion of the gasoline fraction being returned as reflux to the column through pipe 35 by means of a pump, 35a.

Those components of the original stream of 50 cracked products consisting now chiefly of the residual gas, which, however, is saturated with light gasoline fractions, are withdrawn through pipe 36 and are passed through a compressor 37 driven by the internal combustion engine 10 al- 55

ready referred to. Pressure of the gas is thereby increased from say 10 pounds suction to 50 pounds discharge and the gas under such pressure is admitted through pipe 40 into absorber 41 wherein the light ends are washed out of the gas by means of an oil of proper gravity admitted to the top of the absorber through pipe 42, which oil containing the desired light fractions is removed through pipe 43 whereupon it passes 10 through said pipe to absorber still 45 heated by means of a source of heat, not shown, preferably heat exchange, and in which the captured vapors are released and pass out through pipe 46 to a separator 47 serving to separate the products into 15 a rich gas passing out through pipe 48 and a light distillate passing out through pipe 49. The lean oil from the absorber still 45 is returned through pipe 50 to pipe 42 leading to the top of the absorber 41.

20 The lean gas leaves the absorber 41 through the pipe 53, part passing through pipe 54 into either line 55 leading to lean gas storage tank 56 or through line 57, heat exchanger 27 and gas main 14. If necessary, the gas passing through pipe 57 25 may be heated by a coil heater 51a beyond the heat exchanger 27. In the heat exchanger 27 the temperature may be raised from approximately 90 degrees F. to approximately 500 degrees F. Another portion is removed through valve 58 30 and line 59 and passes to various parts of the system such as to vaporizer 17 and superheater 21 where it is burned as fuel.

The rich gas leaving the separator 47 through pipe 48 passes preferably into a pipe 55 leading 35 to gas storage tank 56 wherein it enriches the lean gas, a pump 48a being provided in said pipe 48. From the lean gas storage 56 the gas is circulated to the engines 10, 11 and 12 as by means of pipes 65, reducing valve 65a, 66, 67 leading to 40 engine 10; pipe 68 and branch pipes 69, 70 leading to engines 11 and 12 respectively. Gas from a source not shown may be admitted to the system through pipe 75, compressed by compressor 76, driven by engine 11 and admitted to storage tank 45 77 which constitutes an auxiliary supply. Gas leaves the tank 77 through pipe 78 reducing valve 78a communicating with pipe 70 and also by means of pipe 79 with pipe 67 whereby in an 50 emergency all three engines may be run by gas from tank 77. Such tank is useful, for example, in starting up the system before a supply of cycle gas has been accumulated in the tank 56.

It is possible to omit the compressor 37 and rely upon the back pressure of the internal combustion engines to afford the necessary pressure in the system. The greater the system pressure, however, the easier is the recovery of the light ends in the absorber 41.

In view of the fact that the engines are run 60 with considerable back pressure, it is desirable to supply the gas and air thereto under pressure. Desirably this excess pressure should be about two pounds higher than the back pressure so that where the back pressure is 45 lbs. gauge, the gas 65 and air feed to the engine should be supercharged to 47 lbs. gauge, the air being supercharged by means not shown in the drawing.

In adapting the ordinary internal combustion engine to use in the system described, it is 70 merely necessary to set the valves so that the exhaust valves open early in the power stroke. In this manner, both the temperature of the exhaust gas and the volume delivered from the engine can be accurately governed. The lean 75 gas leaving the absorber 41 would have a fuel

value in itself ample to run the internal combustion engines since it would run as a rule in the neighborhood of 300 to 400 B. t. u. per cubic foot. The rich gas from the condenser 47 on the other hand, has a very much higher fuel 5 value, i. e., in the neighborhood of 1500 to 2000 B. t. u. per cubic foot so that a blend of the two gases may have a fuel value as high as from 800 to 1000 B. t. u.'s or approximately the equivalent of natural gas.

It will be understood that various changes may be made in the arrangement of apparatus without departing from the spirit of my invention or the scope of the appended claims.

I claim:

1. The method of cracking oil in the vapor phase which consists in burning fuel in an internal combustion engine to produce exhaust gases having a temperature in excess of 950° F., vaporizing the oil to be cracked, mingling the oil vapor so produced and said exhaust gases under conditions bringing about cracking of said oil vapor, subjecting the mixture of products of the cracking reaction which include said mingled gases to dephlegmation with recovery of a gasoline-like 25 product, utilizing the energy of said internal combustion engine to compress the uncondensed portion of said mixture of products in order to propel them through the system and to facilitate condensation of the vapors remaining uncondensed, then passing said mixture so compressed to an absorber to strip therefrom said light vapors.

2. In the method of cracking oil in the vapor phase by the agency of a hot gas having a temperature in excess of 950° F., which is mingled with the vapor of the oil to be cracked, the steps of subjecting the mixture of products of the cracking reaction including the mingled gas and combustible gas formed in the cracking reaction 40 to dephlegmation with recovery of a gasoline-like product, leaving a residual gas including said combustible gas, burning this gas in an internal combustion engine and deriving useful mechanical work therefrom and then utilizing the hot 45 exhaust gas from said engine as the cracking agent.

3. In the method of cracking oil in the vapor phase by the agency of a hot gas having a temperature in excess of 950° F. which is mingled with the vapor of the oil to be cracked, the steps of subjecting the mixture of products of the cracking reaction including the mingled gas and combustible gas formed in the cracking reaction to dephlegmation with recovery of a gasoline-like 55 product, leaving a residual gas including said combustible gas, passing said residual gas through an absorber to separate out lean gas from the rich gas and bleeding at least a portion of said lean gas from the system, burning the enriched gas so produced in an internal combustion engine and deriving useful mechanical work therefrom and then utilizing the hot exhaust gas from said engine as the cracking agent.

4. In the method of cracking oil in the vapor phase by the agency of a hot gas having a temperature in excess of 950° F. which is mingled with the vapor of the oil to be cracked, the steps of subjecting the mixture of products of the cracking reaction including the mingled gas and combustible gas formed in the cracking reaction 70 to dephlegmation with recovery of a gasoline-like product, leaving a residual gas including said combustible gas, passing said residual gas through an absorber to separate out lean gas 75

from the rich gas and bleeding at least a portion of said lean gas from the system, burning the enriched gas so produced in an internal combustion engine, utilizing the energy of said internal combustion engine to compress gaseous fuel and feeding said compressed gas to said internal combustion engine, and utilizing the hot exhaust gas from said engine as the cracking agent.

5. The method according to claim 2 in which part of the residual gas is heated by heat derived

from the reaction products and then added to the gas constituting the cracking medium.

6. The method according to claim 2 in which part of said mechanical energy derived from the combustion of the residual gas is used to compress the stream of products passing through the system preferably at the point just prior to the absorber.
